PISTON RING

William S. Loeb, Philadelphia, Pa., assignor to
Wilkening Manufacturing Company, Philadel-
phia, Pa.

Application December 16, 1944, Serial No. 568,408

22 Claims. (Cl. 309—45)

1

The present invention relates to piston rings and it relates more particularly to piston-rings adapted for use in internal combustion-engines.

An object of the present invention is to provide a simple, inexpensive and efficient piston-ring for internal combustion-engines.

Another object of the present invention is to provide a composite oil-control piston-ring made up of a plurality of interchangeable circumferentially-disposed and interlocked segments arranged in self-interlocking and form-retaining relationship.

In my Patent 2,343,915, I have disclosed a self-expanding oil-control piston-ring composed of a plurality of interchangeable segments formed of sheet metal or the like, suitably bent and folded to provide a base and a pair of converging sides having free ends spaced somewhat apart; the segments being interlocked with one another (successive segments pointing in opposite directions) and being adapted to fit within the groove of a piston so as to provide generally triangular, radially-extending oil-passageways axially-intermediate upper and lower, more or less continuous, cylinder-contacting ribs or lands.

The present invention contemplates a further improved piston-ring construction of the general character disclosed in my aforesaid Patent 2,343,915; the improved piston-ring of the present invention being characterized by simplicity of manufacture and assembly and positive support against undesirable relative movement of the segments of the assembled piston-ring during use.

For the purpose of illustrating the invention, there are shown in the accompanying drawings forms thereof which are at present preferred, although it is to be understood that the various instrumentalities of which the invention consists can be variously arranged and organized and that the invention is not limited to the precise arrangements and organizations of the instrumentalities as herein shown and described.

Referring to the accompanying drawings in which like reference characters indicate like parts throughout:

Figure 1 represents a perspective view of one embodiment of the present invention, shown in compressed installed position.

Figure 2 represents a fragmentary perspective view, on a greatly enlarged scale, of the embodiment of Figure 1.

Figure 3 represents a perspective view, on an enlarged scale, of one of the segments making up the embodiment of Figure 1.

Figure 4 represents a perspective view of a segment identical with that of Figure 3, but shown as it appears when rotated vertically through 180° preparatory to assembly with the 5 segment of Figure 3.

Figure 5 represents a vertical cross-sectional view, on an enlarged scale, generally along the line 5—5 of Figure 1.

Figure 6 represents a vertical cross-sectional 10 view generally along the line 6—6 of Figure 5.

Figure 7 represents a fragmentary perspective view generally similar to that of Figure 2 but showing another embodiment of the present invention; parts being broken away better to 15 reveal the construction thereof.

Figure 8 represents a perspective view of one 20 of the segments making up the embodiment of Figure 7.

Figure 9 represents a perspective view of an- 25 other segment complementary to that of Figure 8 and used therewith in making up the embodiment of Figure 7, shown in inverted position relative to the segment of Figure 8.

Figure 10 represents a vertical cross-sectional 30 view generally similar to that of Figure 5 but showing the embodiment of Figure 7.

Figure 11 represents a fragmentary perspective 35 view generally similar to that of Figure 2 but showing still another embodiment of the pres- ent invention.

Figure 12 represents a perspective view gen- 40 erally similar to that of Figure 3 but showing one of the segments making up the embodiment of Figure 11.

Figure 13 represents a fragmentary perspective view, on an enlarged scale, of a further embodiment of the present invention.

Figure 14 represents a perspective view of one 45 of the segments making up the embodiment of Figure 13 shown in inverted position.

Figure 15 represents a vertical cross-sectional view generally similar to that of Figure 6 but showing the embodiment of Figure 13.

In one embodiment of the present invention, 50 shown in Figures 1 to 6 inclusive, I may provide a piston ring formed of a plurality of identical interchangeable segments indicated generally by the reference character 20.

The segments 20 are constructed of sheet metal or the like formed by suitable stamping, bending, folding, grinding and/or other manufacturing operations in any desired sequence.

Each segment includes a base 21, a pair of 55 converging sides 22 and a pair of flanges 23 formed at the ends of the sides 22 and extending

generally parallel to the base 21. The base 21, sides 22 and flanges 23 are preferably integrally formed of sheet metal or the like as hereinabove described.

A gap 24 is provided intermediate the free ends of the sides 22 to permit assembly of a plurality of segments 20 in interlocked position as will be hereinbelow described.

The distance intermediate the free outer edges of the flanges 23 is generally the same as the transverse dimension of the base 21. That is, the total transverse dimension of the two flanges 23 and the intervening gap 24 is generally the same as the transverse dimension of the base 21.

As shown particularly in the isometric perspective views of Figures 3 and 4, the fold-lines 25 forming the junctures of the sides 22 with the base 21, the free edges 27 of the flanges 23 are formed along lines of radius of the cylinder in which the ring is adapted to be used so that the sides of the segments have a radially-inward taper.

However, the fold-lines 26 forming the junctures of the sides 22 with the flanges 23 are oppositely tapered; that is, the fold-lines 26 of each segment diverge radially inwardly. Thus, when the segments are assembled in the manner shown in Figure 2, the fold-lines 26 of successive upper segments fit snugly against the fold-lines 25 of the intermediate lower segment and vice versa.

The outer edges 28 of the segments 20 are given a slight transversely convex curvature corresponding to the curvature of the cylinder in which the piston ring is to be used, so that, when a plurality of the segments are assembled in the manner shown in Figure 1, they form a complete circle of predetermined diameter. The inner edges 29 of the segments 20 may be given a corresponding transversely concave curvature as shown particularly in Figures 1 and 2.

A central inwardly-protruding locking button 30 is integrally formed in the base 21 of each segment 20. Generally semi-circular notches 31 are formed in the flanges 23 adjacent the free edges 27 thereof.

The composite piston ring of Figures 1 to 6 is assembled by interlocking the segments 20 as shown generally in Figure 2. That is, successive segments 20 are arranged with their bases 21 alternately on top and on bottom. One side 21 of each of a pair of adjoining downwardly-opening segments is then positioned within the generally triangular opening defined by the free sides and base of an upwardly-opening segment; the free edges of the enclosed flanges fitting in abutting relationship with the semi-circular notches 31 thereof forming a more or less complete circle fitting about the button 30 so as to maintain the several segments in radially-interlocked position.

It is apparent that, when the above-described step is repeated, a complete piston ring will eventually be formed; the adjoining flanges of each pair of similarly-opening segments being enclosed within the flanges of the intermediate oppositely-opening segment.

Due to the natural resilience of the segments 20, the free sides 22 thereof can be spread apart somewhat momentarily to increase the transverse dimension of the gap 24 so as to facilitate the assembly of the segments into a complete piston ring.

When the segments are assembled as described above within the groove 32 of a piston 33 having one or more oil-draining openings 34 as shown

in Figure 6, the convex edges 28 of the segments contact the cylinder wall 35.

The notches 31 are made slightly oversize relative to the buttons 30 so that a small amount of radial movement of the segments is permitted. Thus, the individual segments may adjust themselves to irregularities in the cylinder wall 35 such as may be caused by wear.

When the segments 20 are fully assembled, a generally continuous ring is formed. That is, there is no "free end" or "gap" as is the case with conventional one-piece piston rings.

The fully-assembled piston ring is so dimensioned as to be compressed slightly when assembled on a piston within a cylinder. Due to the resilience of the sheet metal segments 20, the assembled piston ring has an inherent resilient tension which tends to expand it radially and circumferentially so that there is no need for a separate expander spring as is usually required with conventional one-piece oil-control piston rings.

As can be seen particularly in Figure 5, the abutting sides 22 and flanges 23 of adjoining similarly-disposed segments 20 form radially-extending oil passageways 36 which are generally triangular in cross-section; circumferentially successive passageways 36 having their apices disposed alternately adjacent the top and the bottom of the piston ring.

As previously described, the buttons 30 and the notches 31 provide radial interlock for the segments 20. The converging sides 22 form a circumferential interlock for the segments. Thus, the segments are positively locked in position and the finally assembled piston ring will retain its shape during use and cannot come apart; it being necessary to deliberately spread one of the segments apart (by exerting circumferentially distending forces thereon greater than would normally be encountered during operation) in order to disassemble the ring when desired.

During axial movement of the piston 33 within the cylinder, oil is wiped from the cylinder wall 35 by the cylinder-contacting edges of the segments 20 and is sent through the passageways 36, the groove 32 and the oil draining openings 34, and is returned to the crank-case (not shown), thus providing continuous lubrication for the cylinder wall 35.

The present construction permits various sizes of piston rings to be assembled from standard ring segments by simply employing lesser or greater numbers of segments depending upon the diameter of the cylinder. That is, the construction of the present invention eliminates the necessity for maintaining stocks of many different-size piston rings to fit the cylinders of various make internal combustion engines; segments of a given size and given degree of curvature being capable of assembly into piston rings of relatively widely different diameters.

In Figures 7 to 10, I have shown another embodiment of the present invention. In this embodiment, segments 37-a and 37-b are employed to make up the oil-control piston-ring. The segments 37-a and 37-b are generally the same in form as the segments 20 described in connection with the embodiment of Figures 1 to 6. Thus, each of the segments 37-a and 37-b is composed of a base 38, converging sides 39 having a gap 40 therebetween, and flanges 41. The radially-outer edge of each of the segments 37-a and 37-b may also be transversely convexly curved as described hereinabove in con-

nection with the embodiment of Figures 1 to 6. However, in the embodiment of Figures 7 to 10, the button is omitted from the base of each segment and the semi-circular notches are omitted from the free edges of the flanges.

Instead, the converging sides 39 of the upper segments 37-a are provided with outwardly-protruding buttons 42; corresponding indentations 43 being formed on the inner edges of said sides.

The converging sides of the lower segments 37-b are provided with inwardly-protruding buttons 44.

As can be seen particularly in Figures 7 to 10, when the segments 37-a and 37-b are assembled, the buttons 44 of the segments 37-b fit within the indentations 43 on the upper segments 37-a and thus provide radial interlock between the segments. As shown particularly in Figure 10, radial oil-passageways 45 of generally triangular cross-section are provided by the sides 39 and flanges 41 of successive segments.

The abutting edges of adjoining flanges 41 provide greater circumferential support and minimize undesirable twisting tendencies in the ring.

In Figures 11 and 12, I have shown another embodiment of the present invention. The embodiment of Figures 11 and 12 generally resembles that of Figures 1 to 6; the piston-ring being made up of a plurality of identical interlocking segments 46, each having a base 47, converging sides 48 having a gap 49 therebetween, and flanges 50. Each base 47 is provided with an inwardly-protruding button 51, one edge of each of the said segments being transversely convexly curved to provide a cylinder-contacting surface as described in connection with the embodiment of Figures 1 to 6. The flanges 50 are provided with notches 52 at their free edges. However, the edges of the flanges 50 forward of the notches 52 are formed at an angle as at 53; the angled edges 53 on the two flanges 50 of each segment 46 converging radially outwardly.

As shown particularly in Figure 11, when the piston-ring is fully assembled, the angled edges 53 of the flanges 50 form generally V-shaped notches adjacent the convexly-curved outer periphery of the ring. As a result of this construction, the assembled piston-ring has greater inherent radially-outward tension when installed upon a piston and within a cylinder and is particularly well adapted for use where high unit pressure is desired.

In the embodiment of Figures 11 and 12 I have shown the fold-lines intermediate each base 47 and its sides 48 formed as straight edges or shoulders 63; the straight edges 63 being produced by coining or other suitable operations. These straight edges 63 (as distinguished from the rounded edges shown in Figures 1 to 10) permit the adjoining segments of the final assembled piston-ring to fit more closely with one another and thus to provide more nearly continuous and uninterrupted upper and lower cylinder-contacting annuli.

It is apparent that the embodiments of Figures 1 to 6 and 7 to 10 could also be formed with coined straight-edge fold-lines if so desired.

In Figures 13, 14 and 15, I have shown still another embodiment of the present invention. The oil-control piston-ring of Figures 13, 14 and 15 is assembled from a plurality of identical interlocking segments 54. Each of the segments 54 includes a base 55 having an inwardly-protruding

button 56 formed thereon, converging sides 57 having a gap 58 therebetween, and flanges 59 having semi-circular notches 60 formed at the free edges thereof.

The sides 57 and flanges 59 are cut back from the radially outer convex edges 61 of the base 55.

Thus, as shown particularly in Figure 15, the assembled piston-ring contacts the cylinder wall 35 only along upper and lower spaced ribs formed by juxtaposed upper and lower edges 61, thereby increasing unit pressure of the ring.

Furthermore, since the side edges 62 of the radially outermost portion of each base 55 can be formed as a plane surface (as distinguished from the rounded surfaces at the zones of junction of the sides 57 with the radially inner portion of the base 55) it is possible to attain a closer fit between adjoining bases in the final assembled ring. In this way, more nearly continuous and uninterrupted surfaces are obtained in the upper and lower cylinder-contacting ribs as is desirable, without the necessity for coining operations.

By coining the fold-lines intermediate the bases and their sides in the manner described hereinabove in connection with the embodiment of Figures 11 and 12, it is possible to provide generally flat shoulders throughout the entire radial dimension of the bases and thus to give still more nearly continuous and uninterrupted surfaces for the cylinder-contacting ribs.

The present invention may be embodied in other specific forms without departing from the spirit or essential attributes thereof, and it is therefore desired that the present embodiments be considered in all respects as illustrative and not restrictive, reference being had to the appended claims rather than to the foregoing description to indicate the scope of the invention.

Having thus described my invention what I claim as new and desire to protect by Letters Patent is:

1. An oil-control piston-ring comprising a plurality of individual circumferentially-disposed bent and folded segments of sheet metal or the like, each of said segments being integrally formed and having a base disposed in a generally radial plane, a pair of converging sides extending generally axially from said base and having a gap intermediate their free ends, and a pair of flanges extending generally circumferentially outwardly from the free ends of said sides, successive segments being alternately in upper and lower position with the flanges of successive upper segments disposed in abutting relationship within the converging sides of the intervening lower segment and vice versa.

2. An oil-control piston-ring comprising a plurality of individual circumferentially-disposed bent and folded segments of sheet metal or the like interlockingly engaged in a complete more or less continuous annulus, each of said segments being integrally formed and having a base disposed in a generally radial plane, a pair of converging sides extending generally axially from the sides of said base and having a gap intermediate their free ends, and a pair of flanges extending from the free ends of said sides and lying in a generally radial plane, successive segments being alternately in upper and lower position with the flanges of successive upper segments disposed in abutting relationship within the converging sides of the intervening lower segment and vice versa, the sides and abutting flanges of successive upper segments and successive lower

segments forming generally triangular radially-extending oil-passageways.

3. An oil-control piston-ring comprising a plurality of individual circumferentially-disposed bent and folded segments of sheet metal or the like interlockingly engaged in a complete more or less continuous annulus, each of said segments being integrally formed and having a base, a locking button protruding inwardly from said base, a pair of converging sides extending generally axially from the sides of said base and having a gap intermediate their free ends, and a pair of flanges extending generally circumferentially outwardly from the free ends of said sides, said flanges having generally semi-circular notches formed at their free edges, successive segments being alternately in upper and lower position with the flanges of successive similarly-positioned segments disposed in abutting relationship within the converging sides of the intervening oppositely-positioned segment, the juxtaposed notches of said abutting flanges fitting about said buttons and providing a radial interlock between segments.

4. An oil-control piston-ring comprising a plurality of individual circumferentially-disposed bent and folded segments of sheet metal or the like interlockingly engaged in a complete more or less continuous annulus, each of said segments being integrally formed and having a base disposed in a generally radial plane, a pair of converging sides extending generally axially from the sides of said base and having a gap intermediate their free ends, and a pair of flanges extending from the free ends of said sides and lying in a generally radial plane, successive segments being alternately in upper and lower position with the flanges of successive upper segments disposed in abutting relationship within the converging sides of the intervening lower segment and vice versa, the sides and abutting flanges of successive upper segments and successive lower segments forming generally triangular radially-extending oil-passageways, the sides of one set of segments having locking buttons formed thereon and the sides of the other set of segments having corresponding indentations formed thereon, said buttons and said indentations providing radial interlock between said upper and lower segments.

5. An oil-control piston-ring comprising a plurality of individual circumferentially-disposed bent and folded segments of sheet metal or the like, each of said segments being integrally formed and having a base disposed in a generally radial plane, a pair of converging sides extending generally axially from said base and having a gap intermediate their free ends, and a pair of flanges extending generally circumferentially from the free ends of said sides, successive segments being alternately in upper and lower position with the flanges of successive similarly-disposed segments arranged in abutting relationship within the converging sides of the intervening oppositely-disposed segment and vice versa, and means forming part of said segments for providing complementary radial interlock intermediate successive segments.

6. An oil-control piston-ring comprising a plurality of individual circumferentially-disposed bent and folded segments of sheet metal or the like, each of said segments being integrally formed and having a base disposed in a generally radial plane, a pair of converging sides extending generally axially from said base and hav-

ing a gap intermediate their free ends, and a pair of flanges extending generally circumferentially from the free ends of said sides, successive segments being alternately in upper and lower position with the flanges of successive similarly-disposed segments arranged in abutting relationship within the converging sides of the intervening oppositely-disposed segment and vice versa, and complementary locking means forming part of the bases and flanges of said segments for providing radial interlocking intermediate successive segments of the assembled piston-ring.

7. An oil-control piston-ring comprising a plurality of individual circumferentially-disposed bent and folded segments of sheet metal or the like, each of said segments being integrally formed and having a base disposed in a generally radial plane, a pair of converging sides extending generally axially from said base and having a gap intermediate their free ends, and a pair of flanges extending generally circumferentially from the free ends of said sides, successive segments being alternately in upper and lower position with the flanges of successive similarly-disposed segments arranged in abutting relationship within the converging sides of the intervening oppositely-disposed segment and vice-versa, and complementary locking means forming part of the sides of said segments for providing radial interlock intermediate successive segments for providing radial interlock intermediate successive segments of the assembled piston-ring.

8. An oil-control piston-ring comprising a plurality of individual circumferentially-disposed bent and folded segments of sheet metal or the like, each of said segments being integrally formed and having a base disposed in a generally radial plane, a pair of converging sides extending generally axially from said base and having a gap intermediate their free ends, and a pair of flanges extending generally circumferentially from the free ends of said sides, successive segments being alternately in upper and lower position with the flanges of successive similarly-disposed segments arranged in abutting relationship within the converging sides of the intervening oppositely-disposed segment and vice versa, and complementary buttons and indentations for providing radial interlock therebetween.

9. An oil-control piston-ring comprising a plurality of individual circumferentially-disposed bent and folded segments of sheet metal or the like arranged in the form of a more or less continuous annulus, each of said segments being integrally formed and having a base, a pair of converging sides having a gap intermediate their free ends, and a pair of flanges extending from the free ends of said sides, successive segments being alternately in upper and lower position with one side of each pair of successive upper segments disposed within the converging sides of the intervening lower segment and vice versa, radially inner portions of adjoining flanges being disposed in abutting relationship while the radially outer portions of said adjoining flanges diverge outwardly from each other.

10. An oil-control piston-ring comprising a plurality of individual circumferentially-disposed bent and folded segments of sheet metal or the like arranged in the form of a more or less continuous annulus, each of said segments being integrally formed and having a base, a pair of converging sides having a gap intermediate their

free ends, and a pair of flanges extending from the free ends of said sides, successive segments being alternately in upper and lower position with one side of each pair of successive upper segments disposed within the converging sides of the intervening lower segment and vice versa, said bases having axially inwardly protruding locking buttons formed thereon, said flanges having generally semi-circular locking notches formed at their outer edges, the edges of adjoining flanges being disposed in abutting relationship radially inward of said notches and diverging radially outward of said notches.

11. An oil-control piston-ring comprising a plurality of individual circumferentially-disposed bent and folded segments of sheet metal or the like arranged in the form of a more or less continuous annulus, each of said segments being integrally formed and having a base, a pair of converging sides having a gap intermediate their free ends, and a pair of flanges extending from the free ends of said sides, successive segments being alternately in upper and lower position with one side of each pair of successive upper segments disposed within the converging sides of the intervening lower segment and vice versa, radially inner portions of adjoining flanges being disposed in abutting relationship while the radially outer portions of said adjoining flanges diverge outwardly from each other, and means forming part of said segments for providing radial interlock intermediate successive segments of the assembled piston-ring.

12. An oil-control piston-ring comprising a plurality of individual circumferentially-disposed bent and folded segments of sheet metal or the like, each of said segments being integrally formed and having a base disposed in a generally radial plane, a pair of converging sides extending generally axially from said base and having a gap intermediate their free ends, and a pair of flanges extending generally circumferentially outwardly from the free ends of said sides, successive segments being alternately in upper and lower position with the flanges of successive upper segments disposed in abutting relationship within the converging sides of the intervening lower segment and vice versa, said sides and said flanges being recessed from the outer edges of said bases whereby said bases provide a pair of annular axially-spaced cylinder-contacting ribs.

13. An oil-control piston-ring comprising a plurality of individual circumferentially-disposed bent and folded segments of sheet metal or the like, each of said segments being integrally formed and having a base disposed in a generally radial plane, a pair of converging sides extending generally axially from said base and having a gap intermediate their free ends, and a pair of flanges extending generally circumferentially outwardly from the free ends of said sides, successive segments being alternately in upper and lower position with the flanges of successive upper segments disposed in abutting relationship within the converging sides of the intervening lower segment and vice versa, said sides and said flanges being recessed from the outer edges of said bases whereby said bases provide a pair of annular axially-spaced cylinder-contacting ribs, and complementary locking means forming part of said segments for providing radial interlock intermediate successive segments of the assembled piston-ring.

14. An oil-control piston ring comprising a plurality of individual circumferentially-disposed

5 bent and folded segments of sheet metal or the like, each of said segments being integrally formed and having a base disposed in a generally radial plane, a pair of converging sides extending generally axially from said base and having a gap intermediate their free ends, and a pair of flanges extending generally circumferentially outwardly from the free ends of said sides, successive segments being alternately in upper and lower position with the flanges of successive upper segments disposed in abutting relationship within the converging sides of the intervening lower segment and vice versa, said sides and said flanges being recessed from the outer edges of said bases 10 whereby said bases provide a pair of annular axially-spaced cylinder-contacting ribs, the radially outer portions of said bases having straight side edges whereby more or less continuous straight-line contact is provided at the radially outer portions of the bases of similarly-disposed segments.

15. For use in assembling an oil-control piston-ring, an integral segment of sheet metal or the like having a base, a pair of converging sides having a gap intermediate their free ends, and a pair of flanges extending from the free ends of said sides generally parallel to said base.

16. For use in assembling an oil-control piston-ring, an integral segment of sheet metal or the like having a base, a pair of converging sides having a gap intermediate their free ends, and a pair of flanges extending from the free ends of said sides generally parallel to said base, said base having an inwardly-protruding locking button formed thereon, said flanges having semi-circular locking notches formed at their free edges.

17. For use in assembling an oil-control piston-ring, an integral segment of sheet metal or the like having a base, a pair of converging sides having a gap intermediate their free ends, and a pair of flanges extending from the free ends of said sides generally parallel to said base, said sides having a pair of locking buttons formed thereon.

18. For use in assembling an oil-control piston-ring, a pair of integral segments formed of sheet metal or the like, each having a base, a pair of converging sides having a gap intermediate their free ends, and a pair of flanges extending from the free ends of said sides generally parallel to said base, one of said segments having a pair of locking buttons formed on its sides, the other of said segments having a pair of locking indentations formed on its sides, one of said locking indentations being complementary to one of said locking buttons when said segments are in assembled position.

19. For use in assembling an oil-control piston-ring, an integral segment of sheet metal or the like having a base, a pair of converging sides having a gap intermediate their free ends, and a pair of flanges extending from the free ends of said sides generally parallel to said base, one edge of said segment being transversely convexly curved and being adapted to form part of the cylinder-contacting surface of said piston-ring.

20. For use in assembling an oil-control piston-ring, an integral segment of sheet metal or the like having a base, a pair of converging sides having a gap intermediate their free ends, and a pair of flanges extending from the free ends of said sides generally parallel to said base, one edge of said segment being transversely convexly curved and being adapted to form part of the cylinder-contacting surface of said piston-ring, the side edges of said flanges being tapered adjacent the convex edge of said segment.

21. For use in assembling an oil-control piston-ring, an integral segment of sheet metal or the like having a base, a pair of converging sides having a gap intermediate their free ends, and a pair of flanges extending from the free ends of said sides generally parallel to said base, one edge of said side and said flanges being radially recessed from the corresponding edge of said base.

22. For use in assembling an oil-control piston-ring, an integral segment of sheet metal or the 10

5

like having a base, a pair of converging sides having a gap intermediate their free ends, and a pair of flanges extending from the free ends of said sides generally parallel to said base, one edge of said side and said flanges being radially recessed from the corresponding edge of said base, the sides of the protruding portion of said base being formed as straight-line edges.

WILLIAM S. LOEB.
